UNITED STATES PATENT OFFICE

94,263

DESIGN FOR A SHOE

Samuel Epstein, New York, N. Y., assignor to Ansonia Bootery, Inc., New York, N. Y., a corporation of New York

Application November 20, 1934, Serial No. 54,086

Term of patent 3½ years

To all whom it may concern:

Be it known that I, Samuel Epstein, a citizen of the United States, residing in New York city, county and State of New York, have invented a new, original, and ornamental Design for a Shoe, of which the following is a specification, reference being had to the accompanying drawing, forming part thereof.

In the drawing:

What is claimed is:

The ornamental design for a shoe, as shown.

SAMUEL EPSTEIN.
